UNITED STATES PATENT OFFICE.

GEORGE STAGI, OF LOS ALTOS, CALIFORNIA.

DESIGN FOR AN AUTOMOBILE SIGNAL BOX.

Application filed July 20, 1923. Serial No. 6,814. Term of patent 3½ years.

To all whom it may concern:

Be it known that I, GEORGE STAGI, a citizen of the United States of America, residing at Los Altos, in the county of Santa Clara and State of California, have invented a new, original, and ornamental Design for an Automobile Signal Box, of which the following is a specification, reference being had to the accompanying drawings, forming a part thereof.

The figure is a perspective view of my design.

I claim:

The ornamental design for an automobile signal box, substantially as shown.

GEORGE STAGI.
